DESIGN FOR AN AUTOMOBILE OR SIMILAR ARTICLE

Frank Humer and John R. Morgan, Detroit,
Mich., assignors to General Motors Corporation, Detroit, Mich., a corporation of Delaware

Application December 21, 1933, Serial No. 50,179

Term of patent 14 years

To all whom it may concern:

Be it known that I, Frank Humer, a citizen of the United States of America, residing at 6032 Avery Avenue, Detroit, in the county of Wayne and State of Michigan, and I, John R. Morgan, a citizen of Guatemala, Central America, residing at 1415 Parker Avenue, Detroit, in the county of Wayne and State of Michigan, have invented a new, original, and ornamental Design for an Automobile or Similar Article, of which the following is a specification, reference being made to the accompanying drawing, forming part thereof.

The parts shown in the full lines form the dominant features of the design, and the specific showing of the parts in the dotted lines forms an immaterial part of the design.

We claim:

The ornamental design for an automobile or similar article substantially as shown and described.

FRANK HUMER.
JOHN R. MORGAN.
